UNITED STATES PATENT OFFICE.

MICHAEL H. WHALEN, OF NEW YORK, N. Y.

BOTTLE.

1,093,959.

Specification of Letters Patent. Patented Apr. 21, 1914.

Application filed May 9, 1913. Serial No. 766,640.

To all whom it may concern:

Be it known that I, MICHAEL H. WHALEN, a citizen of the United States, and resident of New York, in the county of New York and State of New York, have invented certain new and useful Improvements in Bottles, of which the following is a specification.

This invention relates to bottles and especially that class which, when filled and had a cap placed on its outlet may be emptied but cannot be refilled on account of certain new and novel parts and arrangement of parts as will be more fully described in the following specification, set forth in the claim and illustrated in the accompanying drawings, wherein:

Figure 1. is a sectional view of the upper end of the bottle. Fig. 2. a similar view reversed to empty the liquid. Fig. 3. is a cross sectional view on the line 3—3. Fig. 4. is a view of the valve from its lower end.

This invention is adapted to furnish a bottle of substantial construction and few parts. The desirable features of a successful bottle of this class are that it must be made for the minimum cost and its parts must operate and not be liable to get out of order. In order to accomplish this result the present invention may be made of glass or porcelain and consists of an ordinary bottle 5 whose neck at its upper end is formed with the shoulders 6 and 7 and its outer surface a short distance below the outlet is provided with screw threads 8 or similar attaching means.

On the top of the neck of the bottle is placed a valve 9 having a stem 10 with channels 11. The outer edge of the valve is provided with a flange 12 of varying thickness so as to fit upon the shoulders 6 and 7 and thus insure a thorough closure against the entrance of liquid from above.

Surrounding the upper end of the neck and the valve is a cap 13 adapted to screw upon the threads 8 and be retained thereon by cement. The upper end of this cap 13 has an opening 14 and its inner walls have grooves 15 leading to this opening so that

while the valve 9 fits closely within the cap 10 and the stem likewise fills the neck of the bottle, the grooves 15 and the channels 11 allow the liquid to pass out beyond the valve and through the opening 14.

In order to keep the valve closed while shipping an outer cap 16 is screwed down on the outer end of the principal cap 13, threads being provided on each cap; and when it is desired to render the device operative, the cap 16 is taken off and its stud 17 which passes down through the opening 14 is removed from contact with the valve which may then move outward and provide an outlet for the liquid.

The valve with its flange and the shoulders on the neck serve as a complete closing means for the mouth of the bottle when the latter is in its upright position and effectively prevent the reentry of any liquid into the bottle. On reversing the position of the bottle the valve slides down in the neck, the flange leaving the shoulders and permitting the liquid to flow down the channels 11, up around the shoulders and down the grooves 15 through the opening 14. This operation cannot take place however as long as the cap 16 is in place so that the contents of the bottle are safe while being transported so that ordinarily when this cap is removed it may be thrown away.

The stem 10, fitting loosely within the neck may move freely but always retains the valve in its operative position. The valve is also guided by the inner walls of the cap 13, the whole moving freely to permit the outward flow of the liquid or so closing the mouth of the bottle as to make the introduction of the liquid impossible. The original filling of the bottle is effected before the valve and caps are placed on the bottle.

It is obvious that the parts may be modified or otherwise arranged without departing from the essential features above described or the scope of the appended claim.

What I claim as new and desire to secure by Letters Patent is:

In a bottle, the combination with a neck having stepped shoulders, of a solid valve

having a stem with channels that are closed when the valve is seated, a flange on the valve and having interior shoulders to fit the shoulders on the neck, an interiorly grooved cap to limit the play of the valve, and a supplemental cap with a stud to prevent the movement of the valve.

Signed at New York in the county of New York and State of New York this 22 day of April A. D. 1913.

MICHAEL H. WHALEN.
